5 Claims. (Cl. 181—59)

This invention relates to a sound attenuating gas conduit, and more particularly to a conduit for conveying, and attenuating the noise level of, a gas stream.

It is the object of our invention to provide a sound attenuating gas conduit which can be simply and easily manufactured from inexpensive tubing, which will have its weight distributed along its length, and which can be tuned to attenuate different and overlapping bands of sound wave frequencies.

It is a specific object of our invention to provide a sound attenuating gas conduit which can be used in association with an internal combustion engine for conveying, and attenuating the noise level of, the exhaust gases emanating from said engine.

In accordance with one form of our invention, there is provided an elongated pipe forming a gas-flow passage and having a plurality of interfitting shells mounted within it. Each of said shells is provided with a closed end which is received in the open end of the next adjacent shell with portions of the walls of the interfitting ends of each pair of said shells being disposed in spaced relation to each other so that the interfitting ends of each pair of shells define a resonator throat. Said throat is in open communication with the gas-flow passage and a resonator volume formed by the adjacent closed ends of said pair of shells and the side walls of the shell in said pair of shells in which the other shell in said pair is received. In this manner, each pair of interfitting shells defines a resonator throat and volume disposed in the gas-flow passage for attenuating the noise level of the gases in said passage.

Other objects and features of our invention will become apparent from the more detailed description which follows and from the accompanying drawings, in which:

FIG. 1 is a fragmentary longitudinal section of a sound attenuating gas conduit embodying our invention;

FIG. 2 is a vertical section taken on the line 2—2 of FIG. 1;

FIG. 3 is an enlarged isometric view of the resonator-forming shell shown in FIG. 1;

FIG. 4 is an isometric view of another embodiment of the resonator-forming shell shown in FIG. 3;

FIG. 5 is a fragmentary longitudinal section of a sound attenuating gas conduit employing another embodiment of our resonator-forming shell;

FIG. 6 is a fragmentary longitudinal section of a sound attenuating gas conduit employing another embodiment of our resonator-forming shell; and

FIG. 7 is a fragmentary longitudinal section of a sound attenuating gas conduit employing another embodiment of our resonator-forming shell.

Our invention is adapted to convey a moving gas stream from one point to another and to attenuate the noise level of said gas stream. Although it may be employed to convey, and attenuate the noise level of, many different kinds of gas streams, it is primarily adapted for use with an internal combustion engine in an automotive vehicle for conveying, and attenuating the noise level of, the exhaust gases discharged from said engine. The sound waves in such exhaust gases extend over a wide range of frequencies, i.e., from about 30 cycles per second to about 1,500 cycles per second. Our invention is adapted to attenuate the noise level of such a range of

2

frequencies, and is particularly well adapted to attenuate the difficult to silence frequencies below 200 cycles per second. Our conduit may be used alone, in which case it extends directly from the exhaust manifold of an engine to the desired gas discharge point, or it may be used in combination with other sound attenuating systems or components, in which case it may constitute one or more short sound attenuating conduits employed with said systems.

As shown in FIG. 1, our invention comprises an elongated pipe 10 forming a gas-flow passage. Said pipe may be in the form of a unitary continuous length of pipe or a series of interconnected pipe sections. Mounted within said pipe is a plurality of elongated, axially aligned, resonator-forming shells 12 conveniently formed from lengths of metal-tubing. Each of the shells 12 comprises a body 14 open at one of its ends and integral and continuous with a neck 16 at its opposite end. The end of the neck 16 remote from the body 14 is closed as at 18. As shown in FIGS. 1 and 2, the neck 16 of each of the shells 12 has a slightly smaller cross-section than the body 14 to permit each pair of said shells to be interfit one within the other, as will be more fully explained hereafter.

The body 14 is provided with one or more deformations adjacent the open end thereof. Such deformations in the embodiment shown in FIG. 3 comprise axially extending inwardly projecting beads 20, formed in the shell side walls and spaced about its circumference, with the inner faces of said beads defining the locus of a circle having a diameter approximating the outer diameter of the neck 16.

In assembling our shells 12, the neck 16 of one of said shells is slid, desirably as a press fit, into the open end of the body 14 of the next adjacent shell. The beads 20 hold the portions of the side walls of the interfitting ends of said shells disposed between said beads in spaced relation to each other so that said wall portions define a resonator throat indicated at 22 in FIG. 2. The closed ends 18 of each pair of interfitting shells form the end walls of a resonator volume indicated at 24 in FIG. 1, with the side walls of said volume being formed by the side walls of the shell in which the next adjacent shell neck 16 is inserted.

As will be apparent, the size of each of the volumes 24 and the length of each of the throats will be determined by the length to which one shell is inserted within the other. As will be understood from known principles of acoustics, the length and cross-sectional area of the throats 22 and the size of the volumes 24 determine the sound wave frequencies which the resonators formed by said volumes and throats will attenuate. If the throats have relatively long lengths and/or relatively large cross-sections, the resonators will attenuate relatively low sound wave frequencies. Conversely, resonators having shorter throats and/or smaller cross-sections will attenuate the higher sound wave frequencies. Thus, the resonators formed by the interfitting shells 12 may be tuned to attenuate different and overlapping bands of sound wave frequencies by controlling the length to which said shells are inserted one within the other, and/or controlling the cross-sectional extent of the beads 20.

The press fit provided by the beads 20 will retain the shells in the desired position of interfitting adjustment during assembly prior to mounting said shells in the pipe 10. With the several shells disposed in such an interfitting engagement said shells may be rigidly secured to the inner wall of the pipe 10 such as by welding or the like to dispose the resonators formed by said shells in direct acoustic and thermal coupling with the gases in said pipe to attenuate the noise level of the sound waves in said gases.

Another embodiment of our shell construction is illustrated in FIG. 4, and comprises a shell 25 having a body 26 open at one of its ends and having its opposite end integral and continuous with a smaller diameter neck 27. The end of the neck 27 opposite the body 26 is closed as at 30, and said neck is provided with outwardly projecting beads 31 formed in its side walls. The outer faces of the beads 31 define the locus of a circle having a diameter approximating the inner diameter of the body 26. In this manner, a plurality of the shells 25 may be inserted one within the other in a press fit to define a series of resonators. The beads 31 hold portions of the side walls of the neck 27 of one shell 25 and body 26 of the next adjacent shell in which said neck is inserted in spaced relation to form a resonator throat in open communication with the gas stream and a resonator volume formed by the adjacent end walls 30 of the interfitting pair of shells and the side walls of the shell in which said neck is inserted. With the shells 25 disposed in the desired interfitting relationship, they may be mounted in the gas-flow passage of a gas-carrying pipe in the same manner as the shells 12.

Another embodiment of our shell construction is illustrated in FIG. 5 in which a plurality of interfitting shells 35 are secured to the inner wall of a pipe 36 defining a gas-flow passage. Each of the shells 35 has a body 37 open at one of its ends and having its opposite end integral and continuous with a smaller diameter neck 38 having its end opposite said body 37 closed as at 39. The neck 38 has an outer diameter approximating the inner diameter of the body 37 so that the shells may be press fit in interfitting relationship to define a series of resonators. One or more outwardly projecting beads 40 are formed in the side walls of the body 37 of each shell so that with the next adjacent shell neck 38 disposed in the open end of said body, said beads and the underlying portions of the side walls of said neck define one or more resonator throats 41 in open communication with the interior of the pipe 36 and a resonator volume 42 formed by the adjacent end walls 39 of the interfitting pair of shells and the side walls of the shell in which the next adjacent shell is inserted.

FIG. 6 illustrates still another embodiment of our shell construction in which a plurality of interfitting shells 44 are secured to the inner wall of a pipe 45 defining a gas-flow passage. Each of the shells 44 has a body 46 open at one of its ends and having its opposite end integral and continuous with a smaller diameter neck 48 having its end opposite said body 46 closed as at 50. The neck 48 has an outer diameter approximating the inner diameter of the body 46 so that the shells may be press fit in interfitting relationship to define a series of resonators. One or more inwardly projecting beads 51 are formed in the side walls of the neck 48 of each shell so that with said neck inserted in the body 46 of the next adjacent shell, said beads 51 and the overlying portions of the side walls of said body will define one or more resonator throats 52 in open communication with the interior of the pipe 45 and a resonator volume 54 formed by the adjacent end walls 50 of the interfitting pair of shells and the side walls of the shell in which the next adjacent shell is inserted.

Although all of the beads formed in the shells shown in FIGS. 1-6 have been illustrated as rectilinear, axially extending beads, such beads may have any desired configuration. It is only essential that said beads be formed in the shells in positions such that they form open ended throats—open to both the gas-flow passage and the resonator volumes.

A sound attenuating conduit employing still another embodiment of our shell construction is illustrated in FIG. 7. As shown, a plurality of interfitting shells 55 are secured to the inner wall of a pipe 56 defining a gas-flow passage. Each of said shells comprises a body 58 open at one of its ends and having its opposite end integral and continuous with a smaller diameter neck 60 having its end opposite said body closed as at 62. The neck 60 has a

smaller outer diameter than the inner diameter of the body 58 and is received in the body 58 of the next adjacent shell to dispose the side walls of the interfitting shell ends in spaced relation to define a resonator throat 63. Said throat is in open communication with the interior of the pipe 56 and a resonator volume 64 formed by the adjacent end walls 62 of the interfitting pair of shells and the side walls of the shell in which the next adjacent shell is inserted.

10 The throats of the resonators formed by the shells shown in FIGS. 1-6 are tuned by adjusting the cross-sectional extent of the beads and the length to which each pair of shells are interfit. In the embodiment shown in FIG. 7, such tuning is controlled by the length to which 15 each pair of shells are interfit and by the relative diameters of the shell necks and bodies. As the diameters of the necks 60 become progressively smaller than the diameters of the bodies 58, the side walls of said necks and bodies are spaced farther apart when the shells are interfit, and 20 the resonators attenuate progressively lower sound wave frequencies.

25 While we have described the modifications of our resonator-forming shells as having a circular cross-section and being adapted to be secured directly to the inner wall of an elongated pipe, it is to be understood that such shells may have any desired cross-sectional configuration and may be mounted within a gas-carrying pipe in any convenient manner.

We claim as our invention:

30 1. In a sound attenuating gas conduit, an elongated pipe forming a gas-flow passage having unrestricted flow at its ends, and a plurality of axially disposed interfitting shells carried within said passage, each of said shells having a closed end received in an open end of the next adjacent shell, first portions of the side walls of interfitting 35 ends of each pair of shells being interfit against each other and second portions of the side walls of said interfitting ends disposed in spaced relation to define a resonator throat in open communication with said gas-flow

40 passage and a resonator volume formed by the adjacent closed ends of said pair of shells and the side walls of the shell in said pair of shells in which the other shell in said pair is received, whereby said resonator throat and volume will attenuate the noise level of the gases in said 45 gas-flow passage.

50 2. In a sound attenuating gas conduit, an elongated pipe forming a gas-flow passage having unrestricted flow at its ends, and a plurality of axially extending interfitting shells carried within said passage, each of said shells having a closed end received in the open end of the next adjacent shell and abutting the inner face of the side walls thereof, one or more elongated projections on the side walls of at least one of the shells in each pair of interfitting shells operatively associated with the side walls of 55 the other shell in said pair of shells to dispose portions of the side walls of the interfitting ends of each pair of shells in spaced relation to define a resonator throat in open communication with said gas-flow passage and a resonator volume formed by the adjacent closed ends of said 60 pair of shells and the side walls of the shell in said pair of shells in which the other shell in said pair is received, whereby said resonator throat and volume will attenuate the noise level of the gases in said gas-flow passage, the length to which one shell in said pair of shells is received in the other shell in said pair of shells being adjustable to 65 adjust the spacing between their closed ends and the length of the interfit of their ends to control the size and length of said resonator volume and throat.

70 3. In a sound attenuating gas conduit, an elongated pipe forming a gas-flow passage having unrestricted flow at its ends, and a plurality of interfitting elongated shells carried within said passage, each of said shells having one of its ends closed and its opposite end open, the closed end of said shell having a smaller cross-section than the 75 open shell end whereby each shell is receivable in the

open end the next adjacent shell, first portions of the side walls of the interfitting ends of each pair of shells press-fit together and second portions of the side walls of said interfitting ends being disposed in spaced relation to define a resonator throat in open communication with said gas-flow passage and a resonator volume formed by the adjacent closed ends of said pair of shells and the side walls of the shell in said pair of shells in which the other shell in said pair is received, whereby said resonator throat and volume will attenuate the noise level of the gases in said gas-flow passage.

4. The invention as set forth in claim 3 with the addition that each of said shells has one or more inwardly extending projections formed in its side walls adjacent its open end and engageable with the side walls of the next adjacent shell received in said open end to form said first portions and to dispose said second portions of said pair of shells between said first portions in spaced throat-forming relation.

5. The invention as set forth in claim 3 with the addition that each of said shells has one or more outwardly extending projections formed in its side walls adjacent its closed end and engageable with the side walls of the next adjacent shell in which said closed end is received to form said first portions and to dispose said second portions of said pair of shells between said first portions in spaced throat-forming relation.
